(57) **CLAIM**

The ornamental design for a battery case for a mobile device, as shown and described.

DESCRIPTION

FIG. 1 is a perspective view of a battery case for a mobile device according to an embodiment;

FIG. 2 is a back side view of the battery case of FIG. 1;

FIG. 3 is a front side view of the battery case of FIG. 1;

FIG. 4 is a top side view of the battery case of FIG. 1;

FIG. 5 is a bottom side view of the battery case of FIG. 1;

FIG. 6 is a left side view of the battery case of FIG. 1;

FIG. 7 is a right side view of the battery case of FIG. 1;

FIG. 8 is a perspective view of the battery case of FIG. 1 with a connector shown in a dislodged configuration according to an embodiment;

FIG. 9 is a back side view of the battery case of FIG. 8;

FIG. 10 is a front side view of the battery case of FIG. 8;

FIG. 11 is a top side view of the battery case of FIG. 8;

FIG. 12 is a bottom side view of the battery case of FIG. 8;

FIG. 13 is a left side view of the battery case of FIG. 8; and,

FIG. 14 is a right side view of the battery case of FIG. 8.

The broken lines are for illustrative purposes only and form no part of the claimed design.

1 Claim, 8 Drawing Sheets
